UNITED STATES PATENT OFFICE.

ALBERT F. DAUM, OF PITTSBURGH, PENNSYLVANIA; ROBERT E. DAUM, ADMINISTRATOR OF SAID ALBERT F. DAUM, DECEASED, ASSIGNOR, BY MESNE ASSIGNMENTS, TO DAUM FUSE AND ELECTRIC MANUFACTURING COMPANY, OF PITTSBURGH, PENNSYLVANIA, A CORPORATION OF PENNSYLVANIA.

FUSE.

Application filed October 24, 1921. Serial No. 509,908.

To all whom it may concern:

Be it known that I, ALBERT F. DAUM, a citizen of the United States, residing at Pittsburgh, in the county of Allegheny and

5 State of Pennsylvania, have invented certain new and useful Improvements in Fuses, of which the following is a specification.

This invention relates to improvements in fuses, and pertains more particularly to constructions of the type in which the fusible element or elements can be readily replaced when the circuit has "blown" the fuse.

Various ways of meeting the problems of renewable fuses have been provided heretofore, the constructions dealing with the problems of construction or of installation or of manufacture in a number of different ways. In this respect the present invention is an improvement in this general field, an improvement designed to provide for maximum efficiency in operation, simplicity in construction, ease in substitution of fusible elements, readily manufactured, and capable of installation at low cost.

25 Primarily, the present invention has as its fundamental the use of an end closure for the tubular casing, said closure forming a support for the fusible element and anchored to the casing, with a cap having a skirt adapted to overlie the end of the casing but free from holding engagement therewith, said cap having means adapted to co-operate with the closure to secure the fusible element against movement, the cap having 30 a form and a relation in the assembly such as to retain it out of contact with the fusible element.

In practice the end closure is provided with a kerf to receive the fusible element 40 either by permitting it to pass therethrough or to form a space within which it may be received, the kerf being of a size to permit of the ready insertion of a fusible element of the proper thickness but insufficient to permit of the use of a thicker element of higher carrying capacity—thus tending to set up the conditions of preventing overloading of the fuse—the closure being arranged to permit the application of pressure on it 45 in such manner as to tend to close the kerf, the walls of the latter thus acting to not only retain the fusible element in position but also ensuring a close contact between the

closure and the fusible element for efficient service, especially under conditions where 55 the invention is used in connection with fuses without blades.

If desired, the fusible element may be led through the end closure and extend alongside the blade and thus be brought into direct contact with the clips for receiving the fuse; and if desirable, either the closure, cap or closure-anchoring means, or all of them, may be of insulating material, so that the fuse—although of the blade type—may be 60 entirely non-metallic in construction with the exception of the fusible element itself, the direct contact feature referred to permitting this result to be obtained; where the blades are omitted, the cap forms the external 65 terminal and the assembly should be metallic, although the closure-anchoring means may, if desired, be of insulating material or non-metallic.

The fuse is made up of a minimum number of parts. Aside from the fusible element—which is of strip form—the fuse, whether of bladed or non-bladed type, includes seven parts, the casing, the two enclosures, the two anchoring elements and 70 the two caps; these may be of various forms, and in the preferred forms there are no tools needed to provide the refilling operation; an additional form carries two screws additional to the parts referred to, this form requiring the use of some screw-turning means 75 to produce the clamping action.

More than a single fusible element may be employed, these extending preferably in parallelism, the additional fusible elements 80 requiring no increase in the number of parts over those required for the single fusible element.

The various parts are of forms such as to enable them to be readily manufactured 85 at minimum cost, thus enabling the invention to be carried into practice at low cost, even where the fuse is of large capacity conditions.

To these and other ends, therefore, the 100 nature of which will be readily understood as the invention is hereinafter more fully disclosed, said invention consists in the improved construction and combination of parts hereinafter more fully described, illustrated in the accompanying drawings and 105

more particularly pointed out in the appended claims.

In the accompanying drawings, in which similar reference characters indicate similar parts in each of the views,⁵

Figure 1 is a view, in longitudinal section, of a fuse of the bladed type, parts being broken away, the two ends being shown as having certain differences in material characteristic.¹⁰

Fig. 2 is an end elevation of a fuse of the type of Fig. 1.

Fig. 3 is an end view of an end closure.

Fig. 4 is an end view of a cap.

Fig. 5 is a transverse sectional view taken intermediate the end closures.¹⁵

Fig. 6 is a view generally similar to Fig. 1, showing the invention applied to a fuse of the non-bladed type.

Fig. 7 is a detail sectional view showing the end closure of a form to house the end of the fusible element.²⁰

Fig. 8 is a view similar to Fig. 5 showing a plurality of fusible elements.

Fig. 9 is a sectional view showing a slightly different arrangement of the means for clamping the fusible element in position.²⁵

Fig. 10 is a sectional view showing another arrangement for producing the clamping action.³⁰

In each of the views, the tubular casing, preferably of insulating material, is indicated at 15, the end-closure at 16, the cap at 17, the closure-anchoring element at 18, and the fusible element at 19. In each form shown the casing is similar, being provided with opposite openings 15^a into which the ends of the element or member 18 extend, the latter being similar in each form.³⁵

The end closure 16 is shown in various forms, but in each the inner portion 16^a is of a size and form to extend into the open end of the casing and practically fit the same, the closure having an annular flange 45 16^b which over lies the end of the casing and of a size to preferably not project beyond the casing in the peripheral dimensions of casing and closure. In each case, the closure-anchoring means 18 extends through the

inner portion 16^a of end closure 16 with the opposite ends of the means located in openings 15^a; as shown in Fig. 6, the means 18, shown as a pin, may extend parallel to the kerf 16^c of the end closure or may extend 55 transverse to the plane of and therefore intersect and pass through the kerf 16^c and the portion of the fusible element located therein.

Kerf 16^c generally extends throughout the axial length of the end closure, as in Fig. 1, for instance, the kerf extending inward from one side of the closure and terminating short of the opposite side so that the two portions of the end closure on opposite sides 60 65 of the kerf are connected by the compara-

tively small connecting portion 16^d, the result being that these portions may be moved toward each other by applying pressure to either portion when the opposite portion is held against movement. However, as shown in Fig. 7, the kerf may enter the end closure at the inner end and terminate short of the outer end of the closure—the connection 16^d in such case being at the end instead of a side—the kerf, in such case, extending entirely across the inner portion 16^a. For convenience in inserting the fusible element the entrance side of the kerf is preferably provided with a flared portion 16^e located at least at the inner end of the closure, the flared walls guiding the fusible element to and into the kerf without requiring "fishing" for the opening.⁷⁰

The kerf 16^c, which may be provided by sawing with a suitable saw of proper dimensions, is preferably of the size to receive the fusible element with a loose fit, the width of the kerf being substantially the same as the thickness of the fusible element strip, the excess width of kerf being slight—simply 80 sufficient to permit the entrance of the strip without cramping. This arrangement serves to limit the size of the strip in cross-section and acts as a preventative to overloading, since a strip having a materially larger 85 carrying capacity will have a thickness such as to tend to expand the kerf and thus increase the size of the inner portion 16^a to a point where it will not enter the casing. With the proper size strip, the loose fit will 90 permit ready entry and at the same time permit the portions of the closure on opposite sides of the kerf to be moved inward relatively sufficient to clamp the strip without straining the connecting portion 16^d.⁹⁵

As a further means for preventing overloading by the use of a strip of excess width, especially in the form in which the connection is at the side, the connection 16^d may have a width such that the kerf within portion 16^a has a length across the closure 100 slightly in excess of that required for the desired strip, thus preventing the positioning of a strip of materially greater width.¹⁰⁵

As shown in Fig. 8, the closure may have a plurality of kerfs 16^c, preferably so arranged that application of pressure on one side of the closure will act to clamp each of a plurality of fusible elements in position. One way in which this can be done is illustrated in this figure, the kerfs being arranged parallel with adjacent kerfs extending from opposite sides of the closure.¹¹⁵

As will be understood, members 18 serve to anchor the closure to the casing, the result being that the cap 17 need not act as the means for retaining the closure in position relative to the casing, it being necessary only that the cap be held sufficiently to prevent its falling off when the assembly is 125 130

completed, the skirt of the cap, when the latter is in position, overlying the ends of members 18 and preventing movement of the latter in a direction to permit removal 5 of the closure 16; as a result, members 18 may have a loose fit to permit ready removal and positioning.

By eliminating the necessity of the cap to retain the assembly in position, it is possible 10 to utilize the cap as a means for applying the pressure to the clamping portions of the closure, or as a carrier for such means. Various ways for obtaining this result are shown. For instance, in Fig. 9, the cap is 15 shown as provided with a set screw 20 at a point where it will, when threaded inwardly, apply pressure on to one of the clamping portions of the closure, and since the opposite clamping portion is held against movement through contact with the cap or the casing, or both, clamping action on the positioned fusible element will be had, the contact of screw and closure serving to sufficiently anchor the cap against moving 20 outward; in Fig. 9, the cap is shown as partially overlying the end of the casing—an arrangement that may be employed with the remaining forms, if desired—but it is 25 obvious that the cap, in this form may be 30 of the type shown in Fig. 1, for instance.

Another way in which this result can be obtained is indicated in Fig. 10, wherein the closure 16 is shown as provided with a short thread zone 16^a—which may have one 35 or more threads—the outer end of the closure being shown as having a bevelled face 16^c. In this form, the cap is provided with a similar zone of internal thread formation, indicated at 17^a, and a bevelled face 17^b on the inturned flange 17^c—the latter flange being common to each of the forms, the remaining forms, however, lacking the face 17^b. In this form, the cap is 40 threaded to position, the bevelled faces 16^c and 17^b co-acting to produce the clamping 45 action as the cap is threaded to position.

However, the preferred mode of securing the desired result is shown more particularly in Figs. 1 to 6, in which the cap and closure have faces relatively arranged in a manner to set up a cam action therebetween when the cap is shifted in a rotative direction while in position on the casing. A simple way of obtaining this result is to 50 offset the opening at the outer end of the cap, so that the inner peripheral face of flange 17^c will be eccentrically arranged with respect to the axis of the cap skirt, as in Fig. 4, the outer end of the closure having a portion similarly offset with respect to the axis of the closure to set up an eccentric relation of this portion—indicated at 16^b with respect to the periphery of the inner portion 16^a. In practice, I prefer to 55 locate the cam portion 16^b at the outer end

of the closure and spaced from the end of casing 15 by an intervening portion of the closure arranged concentric to the closure axis and of a diameter to loosely fit within the cap skirt and therefore capable of co-operating with the cap in the clamping action; Fig. 3 indicates an approximate formation of such end portion 16^b.

Obviously, when the closure is in position, the cap can be readily passed into position 75 relative to the casing and the closure when the eccentric portions have their axes in alinement—the diameters of the two eccentric portions varying slightly to set up a loose relation therebetween. When in this 80 position, the eccentric faces will be in co-operative relation, so that if the cap be moved in the direction of rotation, there will be a relative movement between the two faces 16^b and 17^c tending to bring the high 85 side of the two faces into contact, and since the closure is held from being shifted to compensate for the change in relation—due to contact of the diametrically opposite side of the inner portion 16^a with the casing— 90 and the cap is likewise held from such shift through its contact with the casing and the closure on such opposite side, it will be clear 95 that such movement of the cap will apply pressure on that portion of the closure between such point of contact and the kerf, the result being that the closure is moved to clamp the fusible element in position, the friction developed between the cam faces retaining the cap in its position until released by a movement in the opposite direction. The parts are shown in clamped 100 relation in Fig. 2. As will be clear this rotative movement of the cap can be readily had without changing the position of the cap in the direction of the fuse axis because of the fact that the cap has no holding engagement with the casing, so that the latter has a smooth exterior, the arrangement 105 eliminating the threading of the casing, one of the factors of increased cost of fuses, this characteristic being present in each of the forms.

This arrangement is equally applicable 115 for use in connection with fuses having blades and those without blades, Fig. 1 illustrating the former and Fig. 6 the latter. In the bladed type, the blade 16^c is carried by the closure, either as an integral formation, as in Fig. 7 or at the right in Fig. 1, 120 or as an inserted member as at the left in Fig. 1; with the blade present, kerf 16^c is preferably arranged parallel to the sides of the blade and in proximity thereto to permit the fusible element to extend outward and overlie one side of the blade, as in Fig. 1, thus permitting the use of insulating material for one or more of the assembly members, as indicated at the right in Fig. 1— 125 this end showing the cap, closure and closure 130

anchoring means as of insulating material, the fusible element itself serving as the terminal coating with the clips of the fuse block.

- 5 In the form shown in Fig. 6 the blades are omitted, the cap forming the terminal of the fuse, the fusible element extending to the end of the closure, as at the left in Fig. 6, or projecting beyond the end and folded over 10 the exposed face of the closure, as shown at the right in such figure.

In either form, it will be readily understood that the exposure of the fusible element permits of inspection as to its cross- 15 section and thus enables check to be had on the character of fusible element employed in the fuse.

In the forms thus described the kerf extends throughout the length of the closure 20 16, the connecting portion 16^a being at a side of the closure and extending in the direction of length of the closure; in each of these the fusible element is exposed at the outer end of the closure. In Fig. 7, however, the kerf 25 extends from side to side of the closure, the connecting portion 16^a* being located at the outer end and having its direction of length extending transverse to the axis of the closure. This locates the end of the fusible element within what may be termed a pocket which, however, is open at opposite sides. To obtain the clamping action the closure is elongated as compared with the closure of 30 the remaining forms to provide a portion 35 which extends outward beyond the outer plane of the cap, the kerf thus extending beyond the plane at which the pressure is applied, so that the pressure-application will be made active on a section of the closure capable of movement in the direction to 40 clamp the fusible element.

The structure of Fig. 7 is shown as of the bladed type with metallic members in the assembly. As will be obvious, the blade may 45 be omitted to produce a fuse of the type of Fig. 6; similarly, the assembly parts may be of insulating material as at the right in Fig. 1. In addition, the closure may have a plurality of kerfs arranged in parallelism as in 50 Fig. 8, the connecting portions, however, being at the outer end of the closure. The clamping means may be as in Fig. 1 or as shown in Fig. 9.

As will be understood, the opposite ends 55 of the fuse may have the same assembly or the assemblies may be dissimilar, and this may be to the extent of one end being bladed and the other free from a blade—a combination of Figs. 1 and 6, for instance, such 60 structure operating within clips adapted to receive the fuse of Fig. 6. And such dissimilarity may include the various forms shown in the drawings. And, as indicated in Fig. 6, an insulating washer 25 may be 65 located on the fusible element inside the end

closure, if it be desired to protect the metal of the end closures against the effects of arcing or to close up the exposed portions of the kerf. However, the openings left by the kerfs when the fusible element is of less 70 width than the kerfs, is so small as to practically prevent the passage of flame therethrough and yet permit of the escape of gases when the fusible element blows.

For the purpose of readily distinguishing 75 similar parts in the different forms shown, and to comply with the general rules relative to the use of reference characters, certain of the elements which have the same general action in all of the forms, are given 80 varied lettering. The following will indicate these generally:

The end closure 16 is indicated in changed lettering, as follows: At the right of Fig. 1, it is indicated as 16'; in Figs. 2, 3 and 5, it 85 is referred to as 16, but may obviously be of the material of 16'. In Fig. 6 it is indicated as 16''; in Fig. 7 as 16'''; in Fig. 8 as 16''''; in Fig. 9 as 16''''', and in Fig. 10 as 16'''''.

The cap 17 is indicated at the right in Fig. 1, as 17'; in Figs. 2, 3 and 4, it is indicated as 17, but may obviously be of the material of 17'. In Fig. 9, it is indicated at 17'', and in Fig. 10, it is indicated at 17'''. In the 95 remaining figures the cap is indicated as 17 being similar to the cap at the left of Fig. 1.

The anchoring element 18 is indicated at 100 the right of Fig. 1 as 18'.

While I have herein shown and described various embodiments of my invention and various ways in which they may be combined for service conditions, it will be readily understood that changes and modifications therein may be found desirable or essential in meeting the exigencies of use, and I desire to be understood as reserving the right to make any and all such changes or modifications therein as may be found desirable or necessary, in so far as the same may fall within the spirit and scope of the invention as set forth in the following claims when broadly construed, it being understood, of course, that the specific forms shown are more or less illustrative of the general characteristics of such broad invention.

Having thus described my invention, what I claim as new is:

1. In fuses, a tubular casing of insulating material, and means for supporting a fusible element of strip form to extend longitudinally of the casing, said means including an end closure anchored to the casing and having a kerf adapted to receive a fusible element portion, and a cap removable from the closure and having its skirt overlying the end of the casing, said cap being free from holding engagement with the casing and carrying means operative to place 120 125 130

the end closure in clamping relation with the fusible element portion located therein.

2. A fuse as in claim 1 characterized in that the end closure kerf is normally of a width to provide a loose fit relation with a fusible element having a cross-section to provide the approximate maximum current-carrying capacity condition for the fuse, such kerf width being insufficient to receive

10 a fusible element of similar type but of materially greater current-carrying capacity and support such element in position within the fuse, the presence of an oversize element preventing clamping of the end closure.

15 3. A fuse as in claim 1 characterized in that the end closure and casing are relatively fitted to permit of ready location of a portion of the closure within the casing when

20 the fusible element and kerf are relatively proportioned as to permit ready entrance of the element into the kerf prior to final assembly of the fuse, and prevent such location of the closure portion when a fusible

25 element of similar type but of materially higher current carrying capacity is positioned within the kerf, the presence of an oversize element preventing clamping of the end closure.

30 4. A fuse as in claim 1 characterized in that the kerf is formed with an entrance of flared characteristic extending throughout the length of the end closure to permit of ready positioning of the fusible element within the kerf.

35 5. In fuses, a tubular open-ended casing of insulating material, and means for closing an end of the casing and form a support for a fusible element to extend longitudinally of the casing, said means includ-

40 ing an end closure anchored to the casing and having a portion loosely fitted within the casing end and a portion overlying the end of the casing, said closure having a

45 formation to loosely receive a fusible element portion, and a cap removable from the closure and having its skirt in overlying relation to the end of the casing and free from holding engagement therewith, said

50 cap having a portion in overlying relation to the portion of greater diameter of the closure, said cap carrying means operative to produce a clamping relation between the end closure and such fusible element portion.

55 6. A fuse as in claim 5 characterized in that the cap is formed with an inwardly-extending flange spaced from the end of the casing by the closure portion which it over-

60 lies.

7. In fuses, a tubular casing of insulating material, an end closure therefor and having a portion extending within the casing, said

65 closure having a formation to support a fusible element portion to locate the fusible

element longitudinally of the casing, means for anchoring the closure to the casing, and a cap having its skirt overlying such casing end and the closure anchoring means and being free from holding engagement with the casing, said cap carrying means operative to produce a clamping relation between the end closure and such fusible element portion.

8. In fuses, a tubular casing of insulating material, an end closure therefor, said closure having a kerf extending from end to end of the closure, said kerf being adapted to receive a fusible element portion and extending transversely of the closure and of a length in such transverse direction less than the length of the closure in such direction and with one kerf limit of such transverse length located at the periphery of such closure to provide closure portions free to move toward one another, said closure being anchored to the casing, and a cap having its skirt in overlying relation to the casing and free from holding engagement therewith, said cap carrying means operative to produce relative movement between such closure portions to clamp the fusible element portion in position.

9. A fuse as in claim 8 characterized in that the end closure carries a blade, the kerf being positioned relatively to a face of the blade in such manner that another portion of the fusible element will extend in overlying relation to such blade face when both portions of the fusible element extend in the same plane.

10. In fuses, a tubular casing of insulating material, and means for supporting a fusible element to extend longitudinally of the casing, said means including a closure anchored to the casing and having a formation to support a fusible element portion, and a cap having its skirt in overlying relation to the casing end and free from holding engagement with such end, said cap and closure having complementary means operative to produce a clamping relation between the closure and such fusible element portion.

11. In fuses, a tubular casing of insulating material, and means for supporting a fusible element to extend longitudinally of the casing, said means including an assembly of end closure and cap with the end closure adapted to support a fusible element portion, and with the cap and end closure extending on opposite sides of a wall of the casing, said cap and closure being relatively formed to permit positioning of the cap when the closure is in position and to produce a clamping relation between the closure and fusible element portion by rotative movement of the positioned cap in a single plane.

12. In fuses, a tubular casing of insulating material, and means for supporting a

15 fusible element to extend longitudinally of the casing, said means including an assembly of end closure and cap with the end closure adapted to support a fusible element portion, and with the cap and end closure extending on opposite sides of a wall of the casing, said cap and closure being relatively formed to permit positioning of the cap when the closure is in position and to produce a clamping or releasing relation between the closure and fusible element portion by rotative movement of the positioned cap in the same plane.

16. In fuses, a tubular casing of insulating material, and means for supporting a fusible element to extend longitudinally of the casing, said means including an assembly of end closure and cap with the end closure adapted to support a fusible element portion, and with the cap and end closure extending on opposite sides of a wall of the casing, said cap and closure having complementary means operative to produce a clamping relation between the closure and fusible element portion by rotative movement of the cap in a single plane.

17. A fuse as in claim 16 characterized in that the complementary means provide co-operating faces having characteristics of a cam when the cap is rotated.

18. In fuses, a tubular casing of insulating material, and means for supporting a fusible element to extend longitudinally of the casing, said means including an assembly of end closure and cap with the closure anchored to the casing and adapted to support a fusible element portion, and with the cap and closure extending on opposite sides of a wall of the casing, said closure having

40 a curved face the axis of which is out of alinement with the axis of the closure, said cap having a face adapted to co-operate with the closure face to apply lateral pressure to the closure when the cap is positioned and rotated in a single plane. 45

19. In fuses, a tubular casing of insulating material, and means for supporting a fusible element to extend longitudinally of the casing, said means including an assembly of end closure and cap, with the closure 50 anchored to the casing and adapted to support a fusible element portion, and with the cap and closure extending on opposite sides of a wall of the casing, said cap and closure each having a circular face located to oppose each other in the assembly, with the axis of each face out of alinement with the axis of the part which carries the face, said faces, 55 in one position of the cap being in concentric relation to each other, movement of the cap rotatively being operative to produce an eccentric relation between the faces and produce a camming action therebetween.

20. A fuse as in claim 16 characterized in that the cap movement rotatively is in a 60 single plane.

21. A fuse as in claim 16 characterized in that the radius of the closure face is slightly less than the radius of the cap face.

22. A fuse as in claim 16 characterized in that the cap face is carried by an annular flange projecting inwardly from the skirt of the cap and adapted to overlie a portion of the closure positioned between the closure face and the end of the casing in the 70 assembly. 75

ALBERT F. DAUM.
